(57) **CLAIM**

The ornamental design for lighting device for a vehicle, as shown and described in FIGS. 1-9.

DESCRIPTION

The file of this patent contains at least one drawing executed in color. Copies of this patent with color drawing(s) will be provided by the Patent and Trademark Office upon request and payment of the necessary fee. The color shown on the claimed design forms no part thereof.

FIG. 1 is a side view of a lighting device in accordance with one embodiment of the invention;

FIG. 2 is another view of the assembled lighting device shown in FIG. 1;

FIG. 3 is a front view of the assembled lighting device shown in FIG. 1;

FIG. 4 is another view of the assembled lighting device shown in FIG. 1;

FIG. 5 is a perspective view of the assembled lighting device shown in FIG. 1;

FIG. 6 is a perspective view of the assembled lighting device shown in FIG. 1 illustrating use of a light source such as a bulb, which is not part of the design;

FIG. 7 is another perspective view of the assembled lighting device shown in FIG. 1 illustrating use of a light source such as a bulb, which is not part of the design;

FIG. 8 is a rear view of the lighting device shown in FIG. 1; and,

FIG. 9 is another view of the lighting device shown in FIG. 1.
